Inventor;
Samuel S. Bliss.

United States Patent Office.

SAMUEL S. BLISS, OF NEW BEDFORD, MASSACHUSETTS.

Letters Patent No. 69,394, dated October 1, 1867.

IMPROVEMENT IN ATTACHING THILLS TO CARRIAGES.

The Schedule referred to in these Letters Patent and making part of the same.

TO ALL WHOM IT MAY CONCERN:

Be it known that I, SAMUEL S. BLISS, of New Bedford, in the county of Bristol, in the State of Massachusetts, have invented a new and improved Mode of Attaching Thills to Carriages; and I do hereby declare that the following is a full and exact description thereof, reference being had to the accompanying drawings, and to the letters of reference marked thereon.

Figure 1 is a perspective view of my invention, showing the thill-clip and side irons combined, and clearly illustrating the method of securing the same.

Figure 2 is a plan view of the thill and side irons attached, the latter having conical centres, which are intended to rest in suitable seats in the forward end of the clip-iron.

Figure 3 is a transverse section of the clip-iron, with its conical bearings or seats.

In the construction of couplings for carriage-thills, it is important to have the bearing or axis of motion thereof capable of being "tightened up," so as to compensate for wear, and thus prevent the rattling noise, so disagreeable, and commonly heard during the rapid motion of carriages and other vehicles of like character. To accomplish the foregoing great desideratum is the object of my present invention, and it consists, in a simple and practicable method of securing the thill to the clip-iron by means of conical centres and seats, so secured together and adjusted by means of a clamp-bolt, that the wear consequent upon the continued use of the vehicle can readily be taken up, and thus all the annoyance and difficulties incident to a loose coupling are easily removed.

To enable others skilled in the art to make and use my invention, I will proceed to describe its construction and operation.

A is the thill, constructed in the usual form and manner. To the thill A, by means of clamp-bolts D D, I secure the two side irons B B. On the rear ends of the side irons B B are welded two conical centres or bearings F F, which fit and work in suitable sockets or seats in the clip-iron. C is the clip-iron, which is fitted or secured to the axle in any usual manner, so that its eye and the sockets or seats shall be about on a line with the centre of the axle. In the forward extension of the clip-iron C are two sockets or seats E E, of conical or semi-spherical form, which receive and in which exactly fit and easily work the centres or bearings F F of the side irons B B.

From the foregoing description, the construction and operation of my invention will be readily understood. The clip-iron C being secured to the axle, one of the side irons, B, is secured to the thill by the clamp-bolts D D, which pass through holes arranged in both the thill A and side iron B B, the head of the bolt resting against the face of the side iron. The thill, with the side-iron thus secured, is brought in contact with the clip-iron C, so that the centre or bearing F will enter the socket or seat E of the clip-iron C. The other plate B is then in like manner secured to the thill and clip-iron, and firmly attached to the same by means of the clamp-bolt D. On the end of this clamp-bolt D there is cut a screw-thread, on which works a suitable nut. By means of this screw-thread and nut the side irons are always kept in close contact with both the thill and clip-iron, and all wear upon the centres or bearings F F, or sockets or seats E E, can readily be "taken up" simply by turning the nut on the bolt D.

Having thus fully described my invention, what I claim therein as new, and desire to secure by Letters Patent, is—

1. Securing the side irons B B, when the same are constructed with solid conical bearings or centres F F to the thill A by means of clamp-bolts D D, or in any equivalent manner, substantially as described.
2. The combination of the thill A, side irons B B, having solid conical bearings F F, and clip-iron C, with its conical socket or seats E E, when the same are constructed, arranged, and operated substantially as described, and for the purposes set forth.

SAMUEL S. BLISS.
